FLUID PRESSURE OPERATED PUMP

Franklin M. MacDougall, Kirkwood, Mo., assignor
to Alco Valve Company, St. Louis, Mo., a cor-
poration of Missouri

Application July 22, 1944, Serial No. 546,125

17 Claims. (Cl. 103—46)

1

This invention relates to pumps, and more particularly to a pump which is operated by fluid pressure from a remote source.

An object is to produce an improved fluid pressure operated pump which will have its plunger positively moved in opposite directions by fluid pressure transmitted thereto from a remote source through a single conduit.

Another object of the invention is to produce an improved pump in which the pumping plunger is caused to be reciprocated by changes in fluid pressure developed at a remote point.

A further object is to associate with a pump operated by fluid pressure from a remote source an improved pressure-operated valve for controlling the alternate application of the fluid pressure to opposite sides of a member connected to reciprocate a pump plunger.

Other objects of the invention will become apparent from the following description taken in connection with the accompanying drawing showing the invention embodied in a deep-well pump as by way of example.

In the drawings:

Fig. 1 is a schematic view partly in section of a deep-well pumping system showing both the surface mechanism and the sub-surface pump mechanism;

Fig. 2 is an enlarged sectional view of the sub-surface pump mechanism; and

Fig. 3 is an enlarged sectional view of the fluid pressure developing piston and cylinder combination forming a part of the surface mechanism.

Referring to the drawings in detail, the pumping system shown as being employed as a deep-well pump comprises a pump unit 10 positioned at the bottom of the well casing 11 and a pressure-generating means 12 situated on the surface of the earth. The well casing extending from the surface has positioned therein a production tube or pipe 13 which extends from the surface to the bottom of the casing. At the surface, the tube 13 is supported and connected with the casing by a suitable connector 14. There is also provided a cap 15 for sealing off the top of the tube. From this cap a pipe 16 extends to a receiver or tank 17 to which the liquid at the bottom of the well is to be pumped.

The pump 10 comprises a head member 18 which has depending therefrom a cylinder 19 provided with an end wall 20 having a conical surface which rests in a conical recess in a closure plug 21 for the lower end of the tube 13. This closure plug 21 carries a perforated cylindrical extension 22 extending into the liquid zone at the

2

bottom of the well. The plug also carries a cylindrical extension 23 positioned within the cylindrical extension 22. The head 18 is provided with an integral cylinder 24 which extends downwardly through the cylinder 19 and has its lower end spaced slightly from plug 21. Below the head member 18 and in the cylinder 24 is a member 25 which is arranged to be carried by the head. This member 25 has a cylindrical chamber 26 in which is reciprocably mounted a plunger 27. The plunger extends into the cylinder 24 and carries thereon a piston 28 which is slidable in said cylinder 24. On the lower side of this piston is an extension 29 which extends through an opening 30 in the end wall 20 of the cylinder 24. This extension is of smaller diameter than the plunger 27 in order that the areas on the opposite sides of the piston 28 will be different. A suitable packing 31 seals this extension with the end wall but permits reciprocation of the extension through the end wall. An axial passage 32 extends completely through the plunger 27, piston 28, and the extension 29 and serves as an inlet to permit liquid at the bottom of the well to flow into the chamber 26 ahead of the plunger. The passage is controlled by a ball-check valve 33 which prevents liquid from flowing out of the chamber 26 after it has once entered said chamber. The chamber 26 also has at its upper end an outlet port 34 with which is associated a second ball-check valve 35 arranged to prevent liquid from re-entering the chamber 26 after it has once been discharged therefrom through the outlet port. The passage 36 connects the outlet port 34 with the production tube 13 whereby the discharged liquid from the pump chamber 26 can be received in the tube and then forced out of the top of this tube into the pipe 16 and the receiver.

The head member 18 is arranged to be connected by a pipe 37 to the pressure-generating means 12 on the surface. Communicating with this pipe is a passage 38 in the head member and in the member 25, which passage leads to the chamber 39 within the cylinder 24 and above the piston 28. The head member is also provided with a branch passage 38' which places the pipe 37 in communication with the top end of a bore 40 in the member. Within this bore is a spool-type valve element 41 comprising spaced cylindrical heads 42 and 43 and a reduced connecting part 44 providing an annular groove 45 between the heads.

The spool valve element is arranged to control communication between a passage 46 and passages 47 and 48. Passage 48 is arranged to

connect the interior of the production tube 13 with the bore 40. Passage 41 is arranged to connect the passage 38 with the interior of the bore 40. Passage 46 connects the bore 40 with the interior of the cylinder 19 which, at its lower end, is in constant communication with chamber 49 at the lower side of the piston 28. The passage 46 enters the bore intermediate the passages 48 and 47 and is arranged so that the ends of the spool-type valve element do not affect its communication with the annular groove in the element. The valve element is normally biased to the position shown in Fig. 2 where the passage 48 can communicate with the passage 46, said biasing means comprising a coil spring 50 of predetermined strength. When the valve element is in such position, the passage 47 will be cut off from the passage 46 by the cylindrical portion 43 of the valve element. If the valve element should be moved downwardly its permissible extent against the bias of the spring 50, it will assume a second position where the cylindrical end 42 will cut off the passage 48 and the cylindrical end 43 will open up the passage 47 for communication with the passage 46.

The pipe 37 which extends from the head member 18 of the pump is connected by branch conduits to opposite ends of a cylinder 51 in which is reciprocable a piston 52 having a piston rod 53 connected to a second piston 54 reciprocable in a second cylinder 55. The cylinder 51 is closed at both ends and the piston rod 53 within the cylinder is of predetermined diameter in order that the piston and cylinder can produce predetermined different displacements when operated in different directions. This is apparent since the area of the piston 52 which acts on the liquid at the rear of the piston will be smaller than the area of the head of the piston which acts on the liquid. The branch conduit 37 which connects the forward end of the cylinder 51 to the pipe 37 is provided with a check valve 56 for preventing liquid from entering the cylinder when pressure is being developed by a rearward movement of the piston. The forward end of the cylinder 51 is connected by the pipe 57 to the receiver 17 in order to be supplied with liquid. Associated with this conduit is a filter 58 and a check valve 59.

The piston 54 may be reciprocated within the cylinder 55 by any suitable medium, which may be compressed liquid or compressed air. The medium employed in the particular system shown is a liquid which is placed under pressure by a hydraulic pump 60 driven by prime mover 61. The pump 60 is arranged to alternately deliver liquid under pressure to the opposite sides of the piston 54, and this is accomplished by suitable piping with which is associated a reversing valve 62. This valve is controlled by an oscillating fork 63 actuated by a projection 64 on a rod 65. The rod is carried by arms 66 and 67 pivoted intermediate their ends to a bar 68. A lug 69 on the piston rod 53 is arranged to engage the arms and cause the rod 65 to be moved back and forth to bring about the proper control of the reversing valve. The valve will be reversed at the end of each stroke of the piston 54 so as to cause the piston 54 to be moved in the opposite direction.

Operation

Referring to the operation of this pumping system, the relative sizes of the plunger 27 and the extension 29 have a definite relationship to

each other and the displacement effected by the reciprocation of the piston 52 in the cylinder 51. The chamber 39 above piston 28 will be the only chamber connected to the cylinder 51 during the forward stroke of the piston 52, and the arrangement is such that the volume of fluid displaced into the chamber 39 by the piston 52 during its forward stroke will be sufficient to fill the chamber 39 when the piston 28 is at its lower end as shown in Fig. 2. In connection with the volume of fluid displaced into chamber 39 by the piston 52 during its forward stroke, it is to be noted that such is the volume actually displaced by the piston minus the volume at the rear of the piston since, during this stroke of the piston, liquid is free to bypass into the cylinder at the rear of the piston. During the rearward stroke of the piston 52 the volume of fluid displaced will be equal to the volume of chamber 49 when the piston 28 is at the upper end of its stroke minus the volume of chamber 39 when the piston 28 is at the lower end of its stroke. This is apparent since the valve 41 will be positioned to interconnect both chambers 39 and 49 and the volume to be made up need only be the difference between the chambers.

When the piston 28 and the plunger of the pump are at the positions shown in Fig. 2, the piston 52 will have just completed its forward stroke and be in the position shown in Fig. 3. The valve element will still be in its upper position as shown as the pressure developed during movement of piston 52 is insufficient to overcome the bias of the spring 50. When the piston 52 begins to move rearwardly a high fluid pressure will immediately be created since the piston 28 is no longer free to move downwardly. This pressure will result in the valve element's being moved downwardly so as to cut off the passage 48 and place the chamber 39 in communication with the chamber 49 through the passage 47. The pressure being developed by the piston 52 will now be effective in both chambers 39 and 49, but since a larger area of the piston 28 is exposed to the fluid pressure in chamber 49 than the area exposed to the same pressure in the chamber 39, the piston will be caused to move upwardly thereby moving the plunger 27 upwardly. Since liquid to be pumped has already filled the chamber 26 ahead of the plunger, the upward movement of the plunger will result in the ball valve 33 being held closed and liquid discharged through the port 34 and passage 36 into the production tube 13 where it will be forced upwardly and then through the pipe 16 to the receiver.

When the piston 28 and the plunger 27 have reached their upward extent of travel, the piston 52 in cylinder 51 will have reached the end of its rearward stroke; and at such time the reversing valve 62 will be operated and the piston 52 again moved forwardly. At the time that the reversal of movement of the piston 52 takes place, there will be a drop of liquid pressure and consequently the spring 50 will become effective to move the valve element 41 upwardly to the position shown in Fig. 2 where it will be maintained. As the piston 52 moves forwardly, the pressure being developed will be of such value as to permit the spring of predetermined strength to maintain the valve element in its upper position. With the valve element in such upper position, the passage 47 will be cut off and the passage 48 connected to the passage 46. This position of the valve will result in the chamber 49 below the piston 28 being connected with the production

tube so that the liquid in said chamber 49 can be pushed into the production tube as the piston moves downwardly, the downward movement of the piston 28 being brought about by the fluid pressure being developed by the forward movement of the piston 52. The downward movement of piston 28 carries with it the plunger 27, and a new charge of liquid to be pumped will enter the chamber 26 by the unseating of the inlet ball valve 33. When piston 52 again reaches its forward position as shown in Fig. 3, the volume of fluid displaced will have been sufficient to move the piston 28 to the position shown in Fig. 2, and the suction stroke will be completed. As the piston 52 again moves rearwardly, the valve element 41 will again be acted upon by the higher fluid pressure developed by the piston 52 to again assume its lower position so that both chambers 39 and 49 will be subject to the developed fluid pressure to bring about the upward movement of the plunger 27 in the manner already described.

If it should be desired to change the stroke of the pump plunger 27, this can be done by changing the stroke of the piston 52. With a shorter stroke of the piston 52, the volume displaced by the rearward movement of this piston will be less, and, consequently, the piston 28 will be moved through only part of its available stroke, thus giving a similar partial stroke to the plunger 27. When the piston 52 reverses its movement from a rearward movement to a forward movement, the valve 41 will again be permitted to assume the position in Fig. 2 thus resulting in the piston 28 during its forward stroke returning the pump plunger to the position shown in Fig. 2.

It is obvious that the operation will be unchanged by using two cylinders with single-acting pistons in place of the double-acting pressure-generating piston 52, provided the respective piston areas and piping arrangement are comparable. It is not necessary in order to have the pump operated to provide single-acting pressure-generating pistons of different areas. Where the two pressure-generating pistons have equal areas and displacements, the area on the lower side of piston 28 is twice the area of the upper side. The cylinders will be supplied with parallel supply lines 57 and check valves 58, and they will be connected in parallel to the discharge line through separate check valves 59. The pistons will be alternately operable to displace fluid. During the suction stroke of the pump plunger 27, the rate of displacement of the surface piston will be limited to prevent the pressure rising sufficiently to move the valve element 41 against the spring 56.

Being aware of the possibilities of modifications in the structure disclosed without departing from the fundamental principles of this invention, it is not intended that its scope be limited except as set forth in the appended claims.

What is claimed is:

1. In a pump mechanism for operation by a source of pressure situated at a remote point, a pump having a chamber and a reciprocable plunger therefor, a valve-controlled inlet means to the chamber from a body of liquid to be pumped, a valve-controlled outlet means from the chamber for discharging liquid, a double-acting fluid motor having a movable member connected to the plunger, said member having opposed surfaces of different areas, and fluid pressure-operated valve means controlled by fluid pressure from the source and having an element movable in response to pressure condi-

tions at said source, to one position for connecting the source to apply fluid pressure to one area of the member and movable in response to different pressure conditions at the source to another position for connecting the source to apply fluid pressure to both areas and simultaneously permit the interchange of fluid from one side of the member to the other side.

2. In a pump mechanism for operation by a source of pressure situated at a remote point and having periodic fluctuations in pressure, a pump having a reciprocable plunger, a double-acting fluid motor having a movable member connected to move the plunger, said member having opposed surfaces of different areas the larger of which is to be acted on by fluid pressure from the source to move the plunger in a pumping direction, conduit means for connecting the chambers on both sides of the member to the source and the chamber on the side of the larger area with a discharge port, and valve means for cutting off the chamber on the side of the larger area from the source and placing it in communication with the discharge port, and means controlled by the fluid pressures from the source for controlling the valve means, comprising a pressure chamber to receive pressure from the source to displace the valve, and means applying a predetermined opposing force against the pressure of the chamber to predetermine the pressure at which the valve means moves.

3. In a pump mechanism for operation by a source of variable fluid pressure situated at a remote point, a chamber for receiving liquid to be pumped, a second chamber having an inlet port for receiving fluid from the first chamber and an outlet port for discharging fluid, passage means for conducting liquid from the discharge outlet port, valve means associated with the inlet and outlet ports, a plunger in the second chamber, a fluid motor connected to operate the plunger and having a movable member provided with opposed areas of different sizes, conduit means for connecting the source of fluid pressure to the opposite side of the movable member of the motor, and means comprising a valve element having one position for connecting the source to the motor on the side of its movable member having the smaller area and for connecting the motor on the side of its movable member having the larger area with the passage means and a second position for connecting the source to the motor on both sides of the movable member and for disconnecting the passage means with the motor, and means responsive to variations in fluid pressure from the source for maintaining the valve element in the second position by a lower fluid pressure for permitting the valve element to be in the first position.

4. In a pump mechanism for operation by a source of pressure situated at a remote point and having periodic fluctuations in pressure, a pump having a reciprocable plunger, a double-acting fluid motor having a movable member connected to the plunger, said member having opposed surfaces of different areas arranged so that when both areas are subject to the same fluid pressure a differential force will be present to move the plunger in a pumping direction and when the smaller area is subject to a pressure the plunger will be retracted, and a single valve provided with a spring-biased element having one position for placing the chamber of the fluid motor on both sides of the member in communication with each other and the source and an-

other position for placing the chamber of the fluid motor on the side of the member having the smaller area in communication with the source and the chamber on the other side in communication with a discharge port, said valve element being controlled by fluid pressure from the source and caused to be held in the first position against the bias of the spring by fluid pressure from the source and permitted to assume the second position by spring action as a result of decrease in the pressure from the source.

5. In a deep-well pump for operation by a remote source of fluid pressure, the combination with a production tube, a pump within the tube and comprising a chamber and a plunger reciprocable therein, means for separating the tube from the body of liquid to be pumped from the bottom of the well, a cylinder below the chamber, a piston in the cylinder and connected on one side to the plunger, an extension on the other side of the piston extending into the body of liquid to be pumped, said plunger and extension being of such size as to provide a smaller area on the plunger side of the piston, said plunger, piston and extension being provided with an inlet passage for the pump chamber, a check valve for the inlet passage, means providing an outlet passage from the pump chamber to the production tube, a check valve for the outlet passage, conduit means connecting the source with the cylinder on both sides of the piston and the larger area piston side with the production tube, a single valve for controlling the conduit means and having a spring-biased valve element which in one position places both sides of the piston in communication with the source and with each other and in another position disconnects the larger area side from the source and connects it with the production tube, and means for controlling the positioning of the valve element by different pressures from the source.

6. In combination, pump mechanism comprising a source of pressure including a cylinder and reciprocating piston, means for reciprocating the piston, and means for varying the stroke of said piston, a pump unit situated at a remote point from said source of pressure, conduit means connecting said source of pressure and said pump unit, said pump unit including a chamber and a reciprocable plunger therein, a valve-controlled inlet means to the chamber from a body of liquid to be pumped, a valve-controlled outlet means from the chamber for discharging liquid, and means comprising a double-acting fluid motor and valve means controlled by fluid pressure from said pressure source for causing the plunger to be reciprocated by pressure from said fluid source, the total length of reciprocable travel of said plunger being dependent upon the stroke of said piston of the said pressure source, whereby there obtains a pumping mechanism which may be operated at a partial reciprocal movement of the pump unit plunger or at a full reciprocal movement thereof.

7. In combination, pump mechanism comprising a source of pressure including a cylinder and reciprocating piston, means for reciprocating the piston, and means for varying the stroke of said piston, a pump unit situated at a remote point from said source of pressure, conduit means connecting said source of pressure and said pump unit, said pump unit including a chamber and a reciprocable plunger therein, means for introducing a liquid into and for exiting a liquid from said chamber, and means comprising a double-acting

fluid motor and valve means controlled by fluid pressure from said pressure source for causing the plunger to be reciprocated by pressure from said fluid source, the total length of reciprocable travel of said plunger being dependent upon the stroke of said piston of the said pressure source, whereby there obtains a pumping mechanism which may be operated at a partial reciprocal movement of the pump unit plunger or at a full reciprocal movement thereof.

8. In combination, a pump mechanism adapted for deep well use including a surface unit and a subsurface unit, conduit means connecting said units, said surface unit including a cylinder and reciprocating piston therein, said conduit being operatively connected into said cylinder, means for reciprocating said piston, means to adjust the length of the stroke of said piston, and means for introducing a source of oil into said cylinder for movement under pressure into said conduit, said subsurface unit including a pump having a chamber, a reciprocable plunger therefor, means for introducing a liquid being pumped into said chamber and for exiting it therefrom, a double-acting fluid motor for reciprocating said plunger, liquid passages for liquid under pressure leading to both sides of said motor, and valve means controlling flow of pressure liquid to the lift side of said motor, said valve means being controlled by the pressures set up by the piston in said pressure liquid, said motor and therethrough said plunger being moved a distance on the lift stroke dependent upon the stroke of said piston whereby a partial or full stroke of the plunger obtains as desired.

9. In combination, a pump mechanism adapted for deep well use including a surface unit and a subsurface unit, conduit means connecting said units, said surface unit including a cylinder and reciprocating piston therein, said conduit being operatively connected into said cylinder, means for reciprocating said piston, means to adjust the length of the stroke of said piston, and means for introducing a source of oil into said cylinder for movement under pressure into said conduit, said subsurface unit including a pump having a chamber, a reciprocable plunger therefor, means for introducing a liquid being pumped into said chamber and for exiting it therefrom, a double-acting fluid motor for reciprocating said plunger, liquid passages leading from the conduit to the lift side of said motor, between the lift side and the other side of said motor, and from the lift side to exhaust therefrom, valve means controlling liquid flow in said passages, liquid passages from said conduit to said other side of said motor at all times effective to supply liquid under pressure to said other side of said motor, said valve means being controlled by the pressures set up by the piston in said pressure liquid, said motor and therethrough said plunger being moved a distance on the lift stroke dependent upon the stroke of said piston whereby a partial or full stroke of the plunger obtains as desired.

10. In combination, a pump mechanism including a pump unit, a remotely disposed pressure source, and conduit means connecting said unit and pressure source, said pressure source including a cylinder and adjustable stroke piston therein, said pump unit including a chamber for receiving liquid to be pumped, a reciprocable plunger in said chamber, means for introducing a liquid into and exiting it from said chamber, a two-way fluid motor operatively associated with said plunger for reciprocating the same, and means

for applying pressure from said pressure source to said motor to effect reciprocation thereof including liquid passages and a valve controlling certain of said passages, the length of the pumping stroke of said motor depending upon the length of the stroke of said piston of the pressure source, said pumping stroke of the motor being variable through adjustment of the stroke of said piston.

11. In combination, a pump mechanism including a pump unit, a remotely disposed pressure source, and conduit means connecting said unit and pressure source, said pressure source including a cylinder and adjustable stroke piston therein, said pump unit including a chamber for receiving liquid to be pumped, a reciprocable plunger in said chamber, means for introducing a liquid into and exiting it from said chamber, a two-way fluid motor operatively associated with said plunger for reciprocating the same, and means for applying pressure from said pressure source to said motor to effect reciprocation thereof including liquid passages leading from the conduit to the lift side of said motor, between the lift side and the other side of said motor, and from the lift side to exhaust therefrom, a single valve controlling liquid flow in said passages, liquid passages from said conduit to said other side of said motor at all times effective to supply liquid under pressure to said other side of said motor, the length of the pumping stroke of said motor depending upon the length of the stroke of said piston of the pressure source, said pumping stroke of the motor being variable through adjustment of the stroke of said piston.

12. In a pump, a housing, cylinder means therein, piston means in the cylinder means having opposed operating faces of different areas, a high pressure port in the housing connected to the cylinder means to apply fluid under pressure to the smaller face, passage means to connect said high pressure port to the cylinder means to apply pressure to the larger face, valve means controlling said passage means, yieldable force means acting on said valve means to cause it to maintain the passage means closed, a pressure chamber to receive fluid pressure from said high pressure port, to cause the valve to move against the force means and open the passage means when the fluid pressure in the high pressure port attains a predetermined pressure value, and pumping means having a movable member connected to the piston means to be operated by movement thereof.

13. In a pump, a housing, cylinder means therein, piston means in the cylinder means having opposed operating faces of different areas, a high pressure port in the housing connected to the cylinder means to apply fluid under pressure to the smaller face, passage means to connect said high pressure port to the cylinder means to apply pressure to the larger face, valve means controlling said passage means, yieldable force means acting on said valve means to cause it to maintain the passage means closed, a pressure chamber to receive fluid pressure from said high pressure port, to cause the valve to move against the force means and open the passage means when the fluid pressure in the high pressure port attains a predetermined pressure value, pumping means having a movable member connected to the piston means to be operated by movement thereof, and valved discharge means to exhaust the end of the cylinder means having the larger

piston means face, when said valve means is closed.

14. In a pump, a housing, cylinder means therein, piston means in the cylinder means having opposed operating faces of different areas, a high pressure port in the housing connected to the cylinder means to apply fluid under pressure to the smaller face, passage means to connect said high pressure port to the cylinder means to apply pressure to the larger face, valve means controlling said passage means, yieldable force means acting on said valve means to cause it to maintain the passage means closed, a pressure chamber to receive fluid pressure from said high pressure port, to cause the valve to move against the force means and open the passage means when the fluid pressure in the high pressure port attains a predetermined pressure value, pumping means having a movable member connected to the piston means to be operated by movement thereof, valved discharge means to exhaust the end of the cylinder means having the larger piston means face, when said valve means is closed, and fluid pressure generating means connected to said high pressure port, and adapted to produce alternate high and low fluid pressures in said port, to effect opening of the valve means in response to high pressure conditions, and to permit closing thereof in response to low pressure conditions.

15. In a pump construction, a housing, cylinder means therein, piston means operable in the cylinder means and having opposed fluid pressure receiving faces, means continuously applying fluid pressure to the cylinder means to act against the first pressure receiving face to operate the piston in one direction, a high pressure fluid inlet port in the housing, passage means connecting the inlet to the cylinder means to apply fluid from the inlet to the second piston face, the high pressure on its piston face being adapted to produce a force greater than the opposing force on the first face, valve means in said passage means, yieldable force means normally closing said valve means, fluid pressure-responsive means to open the valve means, said fluid pressure-responsive means being connected to the high pressure inlet port to receive the fluid pressure therein and to open the valve means when said fluid pressure attains a predetermined high value to overcome said force means, and fluid pumping means connected to the piston means to be operated thereby.

16. In a pump, a housing, cylinder means therein, piston means operable in the cylinder means and having a fluid pressure receiving face, means continuously applying force to the piston means to move it in one direction, a fluid pressure inlet in the housing, a passage connecting the inlet to the cylinder to conduct fluid to the said face, valve means in said passage and movable to open and closing positions therein, yieldable force means normally urging the valve means into one of said positions, fluid pressure-responsive means acting on the valve means oppositely to the force means to move the valve means to the other of said positions, the fluid pressure means being connected to the fluid pressure inlet so that it moves the valve means in response to rise in pressure in said fluid pressure inlet, and fluid pumping means connected with the piston means to be operated thereby.

17. In a pump, a housing, cylinder means therein, piston means operable in the cylinder means and having a fluid pressure receiving face, means continuously applying force to the piston

11

means to move it in one direction, a fluid pressure inlet in the housing, a passage connecting the inlet to the cylinder to conduct fluid to the said face, valve means in said passage and movable to open and closing positions therein, yieldable force means normally urging the valve means into one of said positions, fluid pressure-responsive means acting on the valve means oppositely to the force means to move the valve means to the other of said positions, the fluid pressure means being connected to the fluid pressure inlet so that it moves the valve means in response to rise in pressure in said fluid pressure inlet, fluid pumping means connected with the piston means to be operated thereby, said means continuously

5

applying force to the piston means comprising an opposing face on the piston means opposite the aforementioned face, and a fluid pressure passage connecting the inlet to the cylinder means to apply fluid pressure from the inlet to the opposing face.
